RADIAL PISTON PUMP

Howard W. Christenson, Indianapolis, Ind., assignor to General Motors Corporation, Detroit, Mich., a corporation of Delaware

Application December 6, 1954, Serial No. 473,164

2 Claims. (Cl. 103—174)

This invention relates to fluid pumps and more especially concerns a radial piston pump adapted to provide the high pressures required for the operation of servo mechanisms associated with heavy off-the-road vehicles and similar equipment.

The invention has as its principal object to provide a pump answering fully to the indicated requirements which is of simple design as compared to previously proposed pumps and which as a consequence is easier and less costly to fabricate and assemble.

Other objects and features of the invention will appear from the following description.

In the accompanying drawings illustrating the invention in its presently preferred embodiment,

Fig. 1 is a transverse section through the pump; and

Fig. 2 is a section taken at right angles to the section of Fig. 1.

From the drawings it will be seen that the pump housing is formed of two members 10 and 10a secured together by bolts 12 adapted to extend through holes 14 in the member 10. Seals 16 render the joint between the two housing members fluid tight.

Housing member 10 is formed to provide a plurality of cylinders 18 adapted to accommodate pistons 20 reciprocally in the cylinders as later explained. Each cylinder consists of spaced-apart sections 18a and 18b.

The pump is driven through a shaft 19 splined at 22 for connection to a driving member, not shown. Within the pump housing the shaft turns in roller bearing 24 of any suitable design. That portion 26 of the shaft between the bearings will be seen formed as a cam so that on rotation of the shaft, the race piece 28 confining the needle bearings 30 is caused to move eccentrically, resulting in reciprocation of the pistons 20 in the cylinders.

Pistons 20 comprise laterally extending portions 31 for the accommodation of a pair of retainer rings or bands 32 which act to maintain the necessary contact between the pistons and the outer periphery of the race piece 28.

Cylinders 18 are surrounded by a ring or band 35, so fabricated that a measure of clearance is provided between it and the cylinders. The annular space 40 in which the ring is disposed serves as part of a manifold communicating with the discharge port 42. An inlet port 44 connects with each cylinder 18 via a manifold 46 and the annular space 48 between the cylinder sections 18a and 18b.

In Fig. 2, the upper piston is shown in a position of discharge while the lower piston is shown in intake position. Due to the pressure of the oil being forced under the ring

2

35 (note the clearance 50) that portion of the ring beneath or outward of the lower piston is pulled tight against the outer end of the corresponding cylinder, assuring efficient loading of the chamber of the cylinder from the intake manifold 46. As a consequence of the described action, the ring in operation of the pump tends to "walk around" the cylinders, a condition which is highly desirable in that the formation of deposits between the ring and cylinders, which might interfere with the proper functioning of the ring, is largely precluded. In other words, by means of the valving ring, there is achieved what amounts to a self-cleaning pump.

The invention having been thus described and illustrated what is claimed is:

- 15 1. A pump or the like comprising a pair of housing members, one of said members being formed to provide a plurality of radially arranged cylinders, each cylinder being without end walls and having a laterally disposed port in open communication with the corresponding ports of the other cylinders, the other of said housing members including a portion formed to encircle said cylinders in spaced relation and having therein a discharge passage open to the clearance between the outer ends of said cylinders and the said encircling portion and an inlet passage common to said laterally disposed ports, a piston in each of said cylinders, powered means for reciprocating said pistons and a ring element surrounding said cylinders to close the outer ends thereof, said element being wider than such ends and serving as a valve controlling the discharge from the cylinders into said discharge passage.
- 20 2. A pump or the like comprising a pair of housing members, one of said members being formed to provide a plurality of radially arranged cylinders, each cylinder being without end walls and having a laterally disposed port in open communication with the corresponding ports of the other cylinders, the other of said housing members including portion formed to encircle said cylinders in spaced relation and having therein a discharge passage open to the clearance between the outer ends of said cylinders and the said encircling portion and an inlet passage common to said laterally disposed ports, a piston in each of said cylinders, powered means for reciprocating said pistons and a ring element surrounding the cylinders to close the outer ends thereof, said element being wider than such ends and serving as a valve controlling the discharge from the cylinders into said discharge passage.
- 25 3. A pump or the like comprising a pair of housing members, one of said members being formed to provide a plurality of radially arranged cylinders, each cylinder being without end walls and having a laterally disposed port in open communication with the corresponding ports of the other cylinders, the other of said housing members including portion formed to encircle said cylinders in spaced relation and having therein a discharge passage open to the clearance between the outer ends of said cylinders and the said encircling portion and an inlet passage common to said laterally disposed ports, a piston in each of said cylinders, powered means for reciprocating said pistons and a ring element surrounding the cylinders to close the outer ends thereof, said element being wider than such ends and serving as a valve controlling the discharge from the cylinders into said discharge passage.
- 30 4. A pump or the like comprising a pair of housing members, one of said members being formed to provide a plurality of radially arranged cylinders, each cylinder being without end walls and having a laterally disposed port in open communication with the corresponding ports of the other cylinders, the other of said housing members including portion formed to encircle said cylinders in spaced relation and having therein a discharge passage open to the clearance between the outer ends of said cylinders and the said encircling portion and an inlet passage common to said laterally disposed ports, a piston in each of said cylinders, powered means for reciprocating said pistons and a ring element surrounding the cylinders to close the outer ends thereof, said element being wider than such ends and serving as a valve controlling the discharge from the cylinders into said discharge passage.
- 35 5. A pump or the like comprising a pair of housing members, one of said members being formed to provide a plurality of radially arranged cylinders, each cylinder being without end walls and having a laterally disposed port in open communication with the corresponding ports of the other cylinders, the other of said housing members including portion formed to encircle said cylinders in spaced relation and having therein a discharge passage open to the clearance between the outer ends of said cylinders and the said encircling portion and an inlet passage common to said laterally disposed ports, a piston in each of said cylinders, powered means for reciprocating said pistons and a ring element surrounding the cylinders to close the outer ends thereof, said element being wider than such ends and serving as a valve controlling the discharge from the cylinders into said discharge passage.
- 40 6. A pump or the like comprising a pair of housing members, one of said members being formed to provide a plurality of radially arranged cylinders, each cylinder being without end walls and having a laterally disposed port in open communication with the corresponding ports of the other cylinders, the other of said housing members including portion formed to encircle said cylinders in spaced relation and having therein a discharge passage open to the clearance between the outer ends of said cylinders and the said encircling portion and an inlet passage common to said laterally disposed ports, a piston in each of said cylinders, powered means for reciprocating said pistons and a ring element surrounding the cylinders to close the outer ends thereof, said element being wider than such ends and serving as a valve controlling the discharge from the cylinders into said discharge passage.
- 45 7. A pump or the like comprising a pair of housing members, one of said members being formed to provide a plurality of radially arranged cylinders, each cylinder being without end walls and having a laterally disposed port in open communication with the corresponding ports of the other cylinders, the other of said housing members including portion formed to encircle said cylinders in spaced relation and having therein a discharge passage open to the clearance between the outer ends of said cylinders and the said encircling portion and an inlet passage common to said laterally disposed ports, a piston in each of said cylinders, powered means for reciprocating said pistons and a ring element surrounding the cylinders to close the outer ends thereof, said element being wider than such ends and serving as a valve controlling the discharge from the cylinders into said discharge passage.
- 50 8. A pump or the like comprising a pair of housing members, one of said members being formed to provide a plurality of radially arranged cylinders, each cylinder being without end walls and having a laterally disposed port in open communication with the corresponding ports of the other cylinders, the other of said housing members including portion formed to encircle said cylinders in spaced relation and having therein a discharge passage open to the clearance between the outer ends of said cylinders and the said encircling portion and an inlet passage common to said laterally disposed ports, a piston in each of said cylinders, powered means for reciprocating said pistons and a ring element surrounding the cylinders to close the outer ends thereof, said element being wider than such ends and serving as a valve controlling the discharge from the cylinders into said discharge passage.
- 55 9. A pump or the like comprising a pair of housing members, one of said members being formed to provide a plurality of radially arranged cylinders, each cylinder being without end walls and having a laterally disposed port in open communication with the corresponding ports of the other cylinders, the other of said housing members including portion formed to encircle said cylinders in spaced relation and having therein a discharge passage open to the clearance between the outer ends of said cylinders and the said encircling portion and an inlet passage common to said laterally disposed ports, a piston in each of said cylinders, powered means for reciprocating said pistons and a ring element surrounding the cylinders to close the outer ends thereof, said element being wider than such ends and serving as a valve controlling the discharge from the cylinders into said discharge passage.
- 60 10. A pump or the like comprising a pair of housing members, one of said members being formed to provide a plurality of radially arranged cylinders, each cylinder being without end walls and having a laterally disposed port in open communication with the corresponding ports of the other cylinders, the other of said housing members including portion formed to encircle said cylinders in spaced relation and having therein a discharge passage open to the clearance between the outer ends of said cylinders and the said encircling portion and an inlet passage common to said laterally disposed ports, a piston in each of said cylinders, powered means for reciprocating said pistons and a ring element surrounding the cylinders to close the outer ends thereof, said element being wider than such ends and serving as a valve controlling the discharge from the cylinders into said discharge passage.
